Mrs. K. Eckward French.

Inventor,

UNITED STATES PATENT OFFICE.

FRANK L. POPE, OF ELIZABETH, NEW JERSEY.

TELEGRAPHIC REGISTER.

SPECIFICATION forming part of Letters Patent No. 267,929, dated November 21, 1882.

Application filed February 17, 1881. (No model.)

To all whom it may concern:

Be it known that I, FRANK L. POPE, a citizen of the United States, residing at Elizabeth, in the county of Union and State of New Jersey, have invented certain new and useful Improvements in Telegraphic Registers, of which the following is a specification.

My invention relates to the apparatus which is employed to record the characters of the Morse telegraphic alphabet when transmitted over the line from a distant station, and which is technically termed a "telegraphic register."

Prior to the date of my invention the most usual construction of this apparatus consisted of an electro-magnet, armature, armature-lever, and retracting spring, the long arm of said lever being provided with an adjustable steel point or stylus, so arranged with reference to a strip of paper carried past it on a grooved roller moved by clock-work that when the electro-magnet attracted its armature the stylus would be brought forcibly into contact with the moving strip of paper, pressing the same into the grooved roller, and thereby embossing a continuous raised line upon the upper surface of the paper so long as the latter continued to move and the electro-magnet to attract its armature. An objection incident to this organization arises from the circumstance that a considerable degree of force must be exerted by the electro-magnet in order to emboss the paper, necessarily involving the use of a special local battery, which must be controlled by a relay placed in the main circuit, thus adding considerably to the complication and expense of the apparatus necessary at each station. Another objection is that the embossed characters are difficult to read except by the aid of a strong light, which must

also be projected transversely across the paper. Many attempts have heretofore been made to construct an apparatus for recording the characters in ink, thus avoiding both of the before-mentioned objections; but the difficulties in the way of securing a uniform flow of ink at all times and in protecting the same from dust and evaporation have been such as to prevent the general use of such apparatus.

My invention avoids the hereinbefore-mentioned objections and enables me to construct a recording apparatus which requires for its

successful operation electro-magnetic power not greater than that of the relay, which has heretofore been employed for breaking and closing the local circuit of the ordinary register, and effects the marking by mechanism which prevents any flow of ink to the paper, except at such times and in such quantities as are necessary to produce the required result, while the remainder of the ink is stored in an air-tight reservoir and effectually protected from dust and evaporation.

The principal feature of my invention consists in the combination, with the electro-magnet, armature, and armature-lever, of a platen or paper-guide, a strip of paper movable by clock-work, and a fountain-pen of the general construction known as a "stylographic pen," which consists of a marking-point centrally perforated with an ink-duct, a valve which serves to control the flow of ink through said duct, and having a needle or spindle secured thereto, fitting loosely within said ink-duct, whereby the flow of ink is controlled and regulated through the mechanical action of the electro-magnet upon the spindle.

In the accompanying drawings, Figure 1 is a side elevation of a telegraphic register embodying my improvements. Fig. 2 is a plan view of a portion of the same. Fig. 3 is a perspective view of the marking-point and paper-guide, showing their arrangement with reference to each other; and Fig. 4 is a vertical central section of the fountain-pen or marking apparatus.

Referring to Fig. 1, A represents a hollow base, upon which the several parts of the instrument are mounted.

B is a metallic bed-plate, which is secured to the base A in any convenient manner, and forms a support for the hollow metallic case C. The case C incloses a system of clock-work of the usual construction, driven by a weight or spring, the function of which, when released, is to cause a roller, D, to revolve at a uniform rate of speed in the direction indicated by the arrow. This apparatus is common to all telegraphic registers, and, being well known, does not require more particular description here.

E is an electro-magnet of the usual construction, which is fixed upon and supported

by a flexible and resilient bar, F. One end of this bar is firmly secured to the bed-plate B by means of screws f f or otherwise, while its other or free end bears against the end of 5 an adjustable set-screw, C, which passes through the bed-plate B. By means of this screw the free end of the bar F may be forced down or allowed to rise by its own resiliency, and thus the electro-magnet E may be lowered or raised at will, in order to regulate its 10 distance from its armature H. The armature H is carried by a horizontal metallic lever, h, which is pivoted at H' to a bracket or other similar support attached to the case C containing the clock-work. The vertical movement of the armature-lever h may be limited by adjustable set-screws i and i', the former being mounted upon an arm projecting from the standard I and the other upon the lever 15 itself. The retractile spring J is attached to the armature-lever h, and its tension is adjustable to suit the varying strength of the line-current by means of a screw, j, fixed upon a bracket, J', projecting from the case C. A 20 flexible metallic arm, K, is affixed to the lever h by means of a fixed screw, k, and an adjustable screw, k', while its extremity is bent upward and carries a paper-guide, L, the construction of which is best seen in Figs. 3 and 4. 25 It is preferably formed of a thin piece of metal, which is formed into a platen upon which the strip of paper rests, and has its two ends turned over, as shown at l l, leaving an opening on the upper side, within which the writing-point, hereinafter to be described, is 30 brought into contact with the paper.

The apparatus for moving the paper consists of the roller D, hereinbefore referred to, which is capable of being made to revolve at 40 a uniform rate by the action of the clock-work. M is a strip or fillet of paper, which may be taken from a continuous roll, and is made to pass first around the pin m and thence through the guide L over the roller D and along the 45 platform m'. Upon the roller D rests a jockey-wheel, N, which is mounted upon an arm, n, and is made to press firmly upon the strip of paper by means of a spring-arm, n', and an adjustable screw, N', as shown in Fig. 1. The 50 jockey-roller may be lifted from contact with the paper, when required, by means of a lever, O, provided for that purpose.

The interior construction of the fountain-pen will be best understood by reference to Fig. 4. 55 It consists of a reservoir, R, preferably of a spherical or ovoid form, communicating internally with a tube, r, which terminates in a marking-point, P. The marking-point P is centrally perforated with an ink-duct, p, the upper portion of which is enlarged, so as to form a seat for a conical valve, V, which regulates and controls the flow of ink through the duct p. The valve V has attached to it a spindle or needle, v, of smaller diameter than the ink- 60 duct p, and fitted loosely within it, as shown in the figure. When the valve V is in its seat

the lower end of the spindle v projects a little below the marking-point P; but when the paper M is raised by the action of the electro-magnet, so as to come in contact with the marking-point, the spindle is pushed upward and the valve raised, thus permitting the ink contained in the reservoir R to flow through the ink-duct to the paper, provided the pressure of the atmosphere is admitted to act upon the ink in 75 the reservoir.

Inasmuch as the electro-magnet causes its armature to move in response to all signals transmitted through the line, whether intended for the station where the record is to be made, 80 or for some other station, it is obvious that the armature-lever will act upon the spindle and lift the valve at every signal, whether a record is designed to be made or not. It is therefore desirable to provide means to prevent the flow 85 of ink through the marking-point to the paper from taking place except when a communication is to be recorded. This may be most conveniently effected by an automatic device, 90 which will now be described.

Referring to Fig. 4, the top of the ink-reservoir R is closed by a cap, S, which is screwed over an opening in the top of the reservoir, as shown, in such a manner that it may be removed for the purpose of supplying the reservoir with ink when required. The cap S is airtight, with the exception of a small aperture, t, which is ordinarily closed by a valve, T, preferably of india-rubber or other elastic and compressible material. So long as the opening at t is thus closed it will be impossible for the ink to flow from the marking-point, even if the valve V be raised from its seat. When a communication is to be recorded by the apparatus the train of clock-work which causes 105 the paper to move is released by turning the milled head W, which withdraws the detent from the clock-work in a manner well understood.

Attached to the milled head W is a projecting arm, w, to which is pivoted a wire or light rod, w', and the latter is attached to the valve T in the manner shown in Figs. 1 and 4. Consequently whenever the clock-work is started the valve T is simultaneously lifted from the 115 aperture t and air is admitted into the reservoir R, passing down through the air-tube s, attached to the cap, and through openings s' in the lower end thereof, and the ink, upon the opening of the valve V, flows down through 120 the ink-duct v to the paper M.

The construction of the guide L is such that the paper is carried with a positive motion both to and from the marking-point, and thus the possibility of the slack of the paper permitting it to rest against the marking-point between the successive signals is prevented.

In order to prevent the blurring or obliteration of the characters as they pass from the point of the pen, the jockey-wheel N is so placed 125 that it runs on the rear margin of the strip of paper. Consequently the characters pass in 130

front of it and can be seen distinctly at all times after having been traced by the pen.

When the apparatus is used in a main circuit without a relay or local battery, as will usually be the case, the distance between the electro-magnet and its armature may be adjusted to suit the varying condition of the line by raising and lowering the electro-magnet by means of the set-screw G, as hereinbefore explained.

I claim as my invention—

1. The combination, substantially as hereinbefore set forth, of an electro-magnet, armature, and armature-lever, a platen or paper-guide, a fillet of paper movable across said platen, a marking-point centrally perforated with an ink-duct, a valve for controlling the flow of ink through said duct, and a needle or spindle secured to said valve and fitting loosely 20 within said duct, to which a to-and-fro move-

ment is communicated in the direction of its length through said platen or paper-guide.

2. The combination, substantially as hereinbefore set forth, of an electro-magnet, armature, and armature-lever, a platen or paper-guide, a fillet of paper movable across said platen, a tubular marking-point, a normally-closed air-tight ink-reservoir, communicating internally with said marking-point, a valve for admitting external air into said reservoir, and 25 a mechanical connection from said valve to the handle for starting and stopping the mechanism whereby said fillet is moved.

In witness whereof I have hereunto subscribed my name this 16th day of February, 35. 1881.

FRANK L. POPE.
